(57) CLAIM

We claim the ornamental design for a coffee table, as shown and described.

DESCRIPTION

FIG. 1 is a rear perspective view of a coffee table;
FIG. 2 is a top plan view of the coffee table of FIG. 1;
FIG. 3 is a bottom view of the coffee table of FIG. 1;
FIG. 4 is a front elevational view of the coffee table of FIG. 1;

FIG. 5 is a rear elevational view of the coffee table of FIG. 1; and,
FIG. 6 is a side elevational view of FIG. 1, the other side being a mirror image thereof.
